UNITED STATES PATENT OFFICE.

RICHARD F. HOMMEL, OF SAN FRANCISCO, CALIFORNIA.

ELEVATOR ATTACHMENT FOR HYDROPLANES.

1,098,627.

Specification of Letters Patent.

Patented June 2, 1914.

Application filed May 5, 1913, Serial No. 765,970. Renewed April 8, 1914. Serial No. 830,363.

To all whom it may concern:

Be it known that I, RICHARD F. HOMMEL, a citizen of the United States, residing in the city and county of San Francisco and State of California, have invented a new and useful Improvement in Elevator Attachments for Hydroplanes, of which the following is a specification.

My invention relates to elevators to be attached to hydroplanes wherein the said elevator is not only adapted to be shifted to any desired angle but to be shifted backward or forward horizontally so as to increase or decrease the distance between the center of the elevator and the center of gravity of the hydroplane and its objects are, first, to provide improved means for setting the plane of the elevator to any desired angle, second, to provide means for effectively retaining the plane of the elevator in the desired angle, and third, to provide means for shifting the elevator plane backward or forward without disconnecting the same from the controlling device. I accomplish these several objects by means of the device illustrated in the drawings forming a part of the present specification wherein like numerals of reference designate similar parts throughout the said specifications and drawings, and in which—

Figure 1 is a broken plan view of the floats or pontoons of a hydroplane with my device attached thereto. Fig. 2 is a vertical sectional view taken on line X—X of Fig. 1 looking in the direction indicated by the arrow. Fig. 3 is a broken detailed view of the sliding sleeve for maintaining the operating end of the device in a vertical position. Fig. 4 is a broken detailed view showing the manner in which the controlling shaft is connected to the plane of the elevator.

The numeral 1 is used to designate the parallel floats of a hydroplane connected by means of a hollow web 2. Parallel supports 3, having slots 3' therein, are rigidly secured to the front ends of the floats 1. Bearings 4, to which is secured the plane 5, are slidably mounted within the slots 3' of the supports 3. A sector 6, having an arcuate slot 6' and teeth 7, is secured to the inner edge of the plane 5. A disk 8 and a pinion 9, secured to a rotatable shaft 10, are adapted to engage the slot 6' and the teeth 7, respectively, of the sector 6. The shaft 10 is

rotatably mounted within an outer bearing 12 and a sleeve 14 which is feathered to the bearings 15 secured to the under surface of the web 2. A vertical standard 15' is rigidly secured to the inner end of the sleeve 14 and has rotatably mounted therein the vertical shaft 16 provided at its lower end with the gear 17 which meshes with the gear 18 secured to the inner end of the shaft 10. A wheel 19 is rigidly secured to the upper end of the shaft 16 for the purpose of rotating the said shaft 16. 20 is a seat provided for the operator.

The operation is as follows: By rotating the wheel 19 the movement thereof is communicated to the shaft 16 and the bevel gear 17 which in turn rotates the shaft 10 by means of the bevel gear 18 secured thereto. As the shaft 10 rotates the pinion 9 secured to the outer end thereof engages the teeth 7 of the sector 6 and causes the plane 5 to which the said sector is secured to rotate on its bearings 4. The difference of the pitch diameters of the pinion 9 and the teeth 7 of the sector 6 provides a sufficient leverage so that the plane 5 may be held in any desired position by means of the wheel 19. By shifting the whole device forward it is evident that the base of the angle at which the hydroplane is rising will be lengthened while the altitude of the said angle will remain the same. This will, of course, decrease the angle at which the hydroplane is rising without altering the angle of the elevator plane 5. I have provided this means for altering the rise of the hydroplane quickly to be used in case of emergency when there is not time to alter the angle of the plane 5 by means of the slower method through the shaft 10 and hand wheel 19. By moving the wheel 19 forward, the standard 15' and sleeve 14 will also move forward in the feathered bearings 15. The forward end of the said sleeve will engage a collar 10' secured to the shaft 10, and move the shaft 10 and the disk 8 secured to the front end thereof forward also. The disk 8 being within the arcuate slot 6' of the sector 6, will move the said sector 6 and the plane 5 forward in the slots 3' of the supports 3. The standard 15' will be maintained in a vertical position by means of the feather 21 which is secured to the sleeve 14 and is slideable within the bearings 15.

Having thus described my invention what

I claim as new and desire to secure by Letters Patent is—

1. An elevator attachment for hydroplanes comprising suitable parallel supports having longitudinal slots in the outer ends thereof; bearings slidably mounted within the slots; a plane rotatably mounted within the bearings; a sector having teeth on the outer edge and an arcuate slot therein, secured to the inner edge of the plane; a rotatable shaft having a pinion adapted to engage the teeth and a disk adapted to engage the arcuate slot of the sector; and means for moving the rotatable shaft longitudinally.
  2. An elevator attachment for hydroplanes comprising suitable parallel supports having longitudinal slots near the outer ends thereof; suitable bearings slidably mounted within the slots; a plane rotatably mounted within the bearings; a sector secured to the inner edge of the plane and having an arcuate slot therein and teeth on the outer edge thereof; a rotatable shaft having a pinion adapted to engage the teeth and a disk adapted to engage the arcuate slot of the sector; a sleeve slidably secured to the hydroplane and mounted upon the rotatable shaft and adapted to move the said shaft longitudinally; and means secured to the sleeve for rotating the rotatable shaft.
  3. In an elevator attachment for hydroplanes, the combination of suitable parallel supports secured to the front ends of the floats of the hydroplanes and having longitudinal slots near the outer ends thereof; suitable bearings slidably mounted within the slots; a plane rotatably mounted within the bearings; a sector secured to the inner edge of the plane and having an arcuate slot therein and teeth on the outer edge thereof; suitable bearings secured to the hydroplane; a sleeve feathered within the said bearings and having a vertical standard
- rigidly secured to one end thereof; a rotatable shaft within the feathered sleeve having a bevel gear secured to the inner end and a pinion adapted to engage the teeth and a disk adapted to engage the arcuate slot of the sector secured to the plane; and means secured to the vertical standard of the sleeve for rotating the bevel gear on the inner end of the rotatable shaft.
4. In an elevator attachment for hydroplanes, the combination of suitable parallel supports secured to the front ends of the floats of the hydroplane and having longitudinal slots near the outer ends thereof; suitable bearings slidably mounted within the slots; a plane rotatably mounted within the bearings; a sector having an arcuate slot therein and teeth on the outer edge thereof secured to the inner edge of the plane; suitable bearings secured to the hydroplane; a sleeve feathered within the said bearing and having a vertical standard secured to one end thereof; a rotatable shaft within the bearings having a bevel gear secured to the inner end and a pinion secured to the outer end thereof, the pinion being adapted to engage the teeth of the sector; a collar on the said shaft adapted to be engaged by the outer end of the feathered sleeve; a disk on the outer end of the shaft adapted to engage the arcuate slot of the sector; and a shaft rotatably mounted within the vertical standard of the sleeve and having a suitable hand wheel at the upper end thereof and a bevel gear adapted to engage and rotate the bevel gear secured to the inner end of the rotatable shaft secured to the lower end of the said vertical shaft.

In witness whereof I hereunto set my signature in the presence of two subscribing witnesses.

RICHARD F. HOMMEL.
